His Attorney.

UNITED STATES PATENT OFFICE.

HARRY M. STEVENS, OF SCHENECTADY, NEW YORK, ASSIGNOR TO GENERAL ELECTRIC COMPANY, A CORPORATION OF NEW YORK.

SWITCH MECHANISM.

1,421,740.

Specification of Letters Patent. Patented July 4, 1922.

Application filed January 21, 1919. Serial No. 272,347.

To all whom it may concern:

Be it known that I, HARRY M. STEVENS, a citizen of the United States, residing at Schenectady, in the county of Schenectady, State of New York, have invented certain new and useful Improvements in Switch Mechanism, of which the following is a specification.

My invention relates to mechanisms for electric switches and has for its object to provide a mechanism which is universal in its application to a great variety of electric switches, which is adapted for both hand or automatic operation with slight change of parts, which can be moved to unlatching position with a minimum effort and which is, in other particulars, to be more definitely described, an improvement upon similar devices heretofore known in the art.

It is common practice to mount relatively small rupturing capacity switches so that they can be operated by a mechanism located upon a switchboard or panel in front of the switch. Such switches have usually been provided with separate mechanisms including a separate operating member, latching means or escutcheon plate, for each size of switch and still different parts for non-automatic and automatic operation. For automatic operation it has again been necessary to provide independent operating mechanisms dependent upon whether the switch is to be tripped upon overload, underload or low voltage. This necessitated carrying in stock a complete series of operating mechanisms with separate parts each adapted for a specific purpose.

According to my invention, I provide an operating mechanism which is universally adapted, with only a slight alteration or substitution of parts, to perform the function of all the aforesaid separate mechanisms for both automatic and hand operation for all sizes of switches. Furthermore, this mechanism is provided with an extra sensitive latching means which, for automatic operation, can be quickly moved to unlatching position to permit the switch to open free from the handle with a minimum effort. The operating member is also provided with means for quickly and easily releasing the

same from its latched closed position and moving it to opening position in one continuous movement.

The novel features which I believe to be characteristic of my invention will be definitely indicated in the claims appended hereto, while the features of construction and mode of operation will be understood by reference to the following description taken in connection with the accompanying drawing which shows the preferred embodiments of my invention and in which:

Figure 1 is a side elevation of a switch embodying my invention, part of the mechanism being removed, for reasons of clearness, Fig. 2 is a front elevation of the mechanism shown in Fig. 1. Fig. 3 is a top elevation of the operating mechanism for the switch as shown in Fig. 1, and Figs. 4 and 5 are side elevations of the latching means and part of the mechanism taken along the line 3-3 of Fig. 3, in latching and released positions respectively.

In Fig. 1, I have shown at switch 1 of usual construction and, by way of example, a switch of the oil break type. This switch is supported upon a suitable framework 2 and controlled through an operating mechanism mounted in front of the switch on a switch board or panel 3. The operating mechanism for controlling the switch comprises an operating member 4 bifurcated or provided with two similar portions 5, best shown in Fig. 2, carried by or pivotally mounted upon a suitable escutcheon plate 6 secured to the panel or support 3. A connection is provided between the operating member 4 and the actuating mechanism 7 for the switch, extending through a suitable opening in the panel 3 and comprising link members 8, as best shown in Fig. 3, pivoted to and on both sides of the actuating means 7. Cooperating link members 9 are adjustably secured to the members 8 in rigid alignment therewith by means of a bolt 10 or other securing means movable in slots 11 of members 8, as best shown in Fig. 4, whereby the length of the rigid connection can be adjusted depending upon the size of the switch to be operated. The members 9 are offset from one another and are provided at

their outer ends with slots 12 into which extend a pin or pins 13 extending through the portions 5 of the operating member 4, thus providing a lost motion connection with 5 the operating member whereby the member and the rigid connection are independently movable.

Mounted between the links 9 of the rigid connection and forming a connecting means 10 intermediate the rigid connection and the operating member 4 is a normally latched, collapsible connection which in normal or thrust transmitting position serves to rigidly connect the operating member 4 to the members 8 and 9 whereby the thrust or movement of the operating member is transmitted to the rigid connection to operate the switch, the pin 13 being immovable in slots 12. This collapsible connection comprises a toggle 20 having cooperating members 14 and 15, best shown in Fig. 4, toggle link 14 having two engaging surfaces 14^a and 14^b, and pivoted at one end upon pin 13 between the portions 5 of the operating member 4, while toggle links 15, comprising duplicate members, are pivotally secured at one end upon a bearing 16 between links 9 of the rigid connection. The links 14 and 15 are pivotally connected together intermediate their ends. The links 30 15 are also provided with ears 17, best shown in Fig. 3, which cooperate with the links 9 to limit the movements of the toggle to latched position and these links also have extended portions 18 provided to operate a 35 signal or indicating device, such as a bell alarm switch 19, when the toggle collapses.

For holding the collapsible connection 14-15 in rigid, latched, or thrust transmitting position, I provide a latching means 40 comprising a main latch or member 20 pivotally mounted upon bearing 16 and having a latching recess 21 adapted to engage the engaging surface 14^a of toggle link 14, along an inclined plane whereby the main latch 20 restrains the toggle in thrust transmitting position. Cooperating with the main latch 20 is a secondary or auxiliary latching member 22 pivotally carried by the latching member 20 and preferably cleved therein. 50 The auxiliary latching member 22 is provided with an engaging or latching portion 23 which cooperates with the engaging surface 14^b of toggle 14 to restrain the main latch 20 in latching position. The member 22 is also provided with a tail portion 24 and also a stop 25 to limit the movement of the latch 22 in latching position. The latching member 20 is limited in its movement to both restraining and releasing position by 55 a pin 27 engaging a recess 28 in the member.

The escutcheon plate 6 carries near the top thereof, within a suitable enclosure 29, a circuit controlling device or switch 19 biased to open position and adapted to be engaged 60 by the portions 18 of toggle link 15 and

moved to circuit closing position to control a bell alarm or other indicating device to indicate an automatic opening of the switch. The operating member 4, in switch closing position, engages the front portion of the 70 inclosure 29, to which is pivotally supported a latching pawl 30 biased to latching position and adapted to extend between the portions 5 of operating member 4 and engage a pin 31 carried thereby, to restrain the 75 member 4 in its closed position. For automatically moving the latching pawl 30 to releasing position, means is provided for releasing the latch 30 during the initial movement of the operating member to circuit 80 opening position. This means comprises a handle 32 for the operating member pivotally carried between the free ends of bifurcating portions 5 thereof and movable independently of the operating member. Carried by the handle 32 and preferably integral therewith is a depending portion or releasing member 33 extending between the portions 5 of the operating member 4, as shown in Figs. 1 and 2, and terminating in a 90 finger 34. The extent of movement of the portion 33 by the handle 32 is limited in one direction by pin 31 and in the opposite direction by a pin 35. In the initial movement of the operating member 4 in switch 95 opening direction, the handle 32 is rotated about its pivotal connection, causing releasing member 33 with its finger 34 to engage the latch 30 and move it free of pin 31 into releasing position whereupon continued 100 movement of the handle carries the operating member with it as a unit to switch opening position. As the collapsible connection 14-15 is held latched, the thrust of the operating member 4 is transmitted through 105 rigid connections 8-9 to move the switch from closed to open position in one continuous movement. With the return of the operating member to closed position, the latch 30 automatically engages the pin 31 110 and restrains the switch in closed position. This type of mechanism, as described, is used for all sizes of switches of the non-automatic type. The escutcheon plate 6 also carries, 115 preferably integrally related thereto, a compartment 36 at the lower end thereof adapted to contain a removably positioned electro-responsive device when automatic operation of the switch is desired.

When it is desired to change the mechanism from a non-automatic to an automatic type, a tripping member 37 is pivotally supported on an extension of the compartment 36 in position to engage the tail 24 of latch 22 when moved to tripping position and secured to the member 37 is an adjustable stop 38 to vary the distance of travel of the member when moved to tripping position. The tripping member may be actuated by hand for non-automatic mechanisms or by an elec- 125

tro-responsive means responding to over-load, underload or low voltage in automatic mechanisms.

For automatic operation in response to 5 over-load, an electroresponsive device is removably positioned within the compartment 36 with one, two or three windings or solenoids 39 dependent upon conditions, each of which in response to over-load current of a 10 predetermined amount will raise its plunger, with or without a time delay, to operate the tripping means 37 and move it to tripping position. If low voltage protection is desired, an auxiliary device, of well known 15 type, is mounted upon the panel 3 adjacent the operating member 4 and operatively related to the tripping member 37. In the illustration shown in Fig. 2, I have provided a low voltage device of the hinged armature 20 type, in which the armature 40 is biased to tripping position but is normally restrained in an upright position by a voltage winding. When the voltage falls below a predetermined amount, the armature 40 is released 25 and due to gravity falls to release a spring device, not shown, to give the arm 41 a sudden blow. As the arm 41 extends into the path of and below the tripping member 37, the member 37 is consequently moved to 30 tripping position with a snap action. For underload protection a similar device may be used substituting a current for a voltage winding which permits the release of the armature 40 when the current falls below a predetermined amount. It is understood 35 that either one or all three removably positioned devices may be used dependent upon conditions, to change a non-automatic switch to one of automatic character.

40 The operation of the mechanism of the non-automatic type is apparent, the collapsible connection 14-15 being held constantly rigid to transmit the thrust of the operating member 4 to the switch parts in switch opening and closing directions. Depending on the size of the switch, the rigid connection comprising links 8 and 9 is adjustable in length by means of bolt 10 and slot 11, whereas the collapsible connection 14-15 is unchanged for all sizes of 45 switches.

When automatic operation is desired, all 50 that is required is the addition of the desired electroresponsive means to the already existing structure and the tripping member 37 automatically movable thereby, moves the latch 22 to releasing position, as shown in dotted lines in Fig. 4. The movement of the latch 22 to releasing position leaves the main latch 20 unrestrained and it quickly moves to releasing position causing the collapse of members 14 and 15 of the collapsible connection to the position shown in Fig. 5. The collapse of this connection permits the movement of members 8 and 9 of the rigid con-

nection together with the switch parts to switch opening position independent of the operating member 4, the rigid connection moving horizontally by means of the slots 12, as shown in Fig. 5. The movement of 50 members 15 to collapsed position carries portions 18 into engagement with the control switch 19 moving it to closed position where a circuit is completed to operate any signal device to notify the operator of the 55 automatic opening of the switch.

By moving the operating member to switch opening position, the initial movement of which releases the latch 30, as has been described, the pin 13 moves along slot 80 12 and reaching the limit of the same carries the toggle 14 and 15 to latching or reset position. The operating member 4 is thereby again in thrust transmitting position whereupon a movement of the member in 85 switch closing direction is transmitted by the latched connection 14-15, and links 8 and 9 to the switch parts which are correspondingly moved to closed position.

In accordance with the provisions of the 90 patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:— 100

1. In a mechanism for controlling an electric switch, the combination with an operating member, of a connection intermediate said member and said switch including a pivoted member having two engaging surfaces, a pivotally mounted main latching member having a portion cooperating with one of said engaging surfaces, and a second latching member pivoted to said main latching member and cooperating with the other 110 engaging surface of said pivoted member.

2. In an operating mechanism for electric switches, an operating member connected to a switch, latching means mounted independently of said member for restraining said member in closed position, a handle for said member movable about a fixed point independently of said operating member, an extension carried by said handle for moving said latching means to releasing position 120 during the initial movement of said handle in opening direction whereby subsequent movement of said handle moves said operating member to open position free of restraint.

3. In an operating mechanism for electric switches, an escutcheon plate, an operating member pivotally mounted on said plate, and a latch secured to said plate biased to restrain said operating member in closed 130

- position, a handle for said operating member movable independently of said member, a depending member carried by said handle and movable thereby to release said latch, a stop carried by said operating member and engaged by said depending member whereby continued movement of the handle in releasing direction opens said operating member.
10. 4. In an operating mechanism for electric switches, a bifurcated operating member, a pin between the bifurcating portions thereof, latching means mounted independently of said operating member and extending between said bifurcating portions to engage said pin to hold said operating member in closed position, a handle for said operating member pivoted between the free ends of said bifurcating portions and movable independently of said operating member, a depending portion carried by said handle and movable thereby to cause the release of said latching means, whereby said operating member is released and moved to open position in one continuous movement.
5. In an operating mechanism for an electric switch, an operating member, means connecting said member to said switch including a collapsible connection, and means for automatically collapsing said connection to permit said switch to open independently of said operating member, one of the members of said collapsible connection being adapted when moved to collapsed position to mechanically operate a device for indicating the automatic opening of said switch.
6. In an operating mechanism for an electric switch, an escutcheon plate, an operating member carried by said plate, a connection between said operating member and said switch including a collapsible connection comprising a movable member having two engaging portions, a main latching member arranged to engage one of said portions and an auxiliary latching member arranged to engage the other of said portions and said main latching member to cause said main latching member to hold said collapsible connection rigid, a tripping member arranged to release said auxiliary latching member, a receptacle integrally related to said plate, and electroresponsive means positioned in said receptacle for automatically controlling said tripping member.
7. In an operating mechanism for an electric switch, an operating member, means connecting said member to said switch including cooperating links rigidly connected and forming a connection the length of which is adjustable, a toggle member pivotally carried by said operating member having two engaging surfaces, a cooperating toggle member carried by said links, a main latch carried by said links cooperating with one of said engaging surfaces to maintain said toggle in restrained position, and an auxiliary latch pivotally carried by said main latch cooperating with the other of said engaging surfaces to restrain said main latch in latching position.
8. In an operating mechanism for an electric switch, an operating member, a connection between said operating member and switch secured to said member through a lost motion connection whereby said switch and operating member are movable independently, means for holding said connection and member in thrust transmitting relation comprising a collapsible toggle having one member carried by said operating member and a cooperating member carried by said connection, and latching means for holding said toggle members in latching position, and means for automatically causing the collapse of said toggle members in response to predetermined abnormal conditions to permit said switch to open independently of said operating member.
9. In an operating mechanism for an electric switch, an operating member, a rigid connection secured at one end to said switch and at the other end to said operating member through a lost motion connection, and a collapsible connection intermediate said rigid connection and said operating member comprising cooperating toggle members, a main latching member adapted to engage one of said toggle members to restrain said toggle in thrust transmitting position and an auxiliary latching member cooperating with said one of said toggle members to restrain said main latching member in latching position.
10. In an operating mechanism for an electric switch, a bifurcated operating member, a pin between the bifurcating portions of said member, links secured to each end of said pin through slots, cooperating links connected to said first mentioned links and to said switch to form a rigid connection, a toggle member pivoted upon said pin intermediate said bifurcating portions, a cooperating toggle member pivotally mounted between said first mentioned links, a main latching member between said first mentioned links for holding said toggle members in position to transmit the thrust of said operating member to said rigid connection and a secondary latching member for restraining said main latching member in latching position.
11. In an operating mechanism for an electric switch, an operating member, a rigid connection between said switch and said operating member provided with a slot, a pin carried by said operating member movable in said slot, and means for transmitting the thrust of said operating member to said rigid connection including a collapsible con-

nection between said rigid connection and said operating member, said collapsible connection comprising a toggle member carried by said operating member pivotally supported on said pin, a cooperating toggle member pivotally secured to said rigid connection, a main latch for holding said toggle members in thrust transmitting position and an auxiliary latch pivotally carried by said main latch and cooperating with said toggle members to hold said main latch in latching position.

12. In an operating mechanism for an electric switch, the combination with an operating member, links secured to said operating member through a lost motion connection and to said switch to form a rigid connection, means whereby the length of said connection can be adjusted, means carried intermediate said operating member and said links adapted to rigidly connect said operating member to said links comprising collapsible toggle members, a main latch for holding said toggle members in thrust transmitting position, and an auxiliary latch for holding said main latch in latching position, a tripping member for releasing said latches whereby said toggle members collapse and permit said switch to open independently of said operating member, and removably positioned means for automatically controlling said tripping member in response to predetermined abnormal conditions in the circuit of the switch.

In witness whereof, I have hereunto set my hand this 20th day of January, 1919.

HARRY M. STEVENS.
